IMPACT FORGING

Alfred H. Oelkers, Chicago, Ill.

Application August 7, 1935, Serial No. 35,037

19 Claims.

(Cl. 78—20)

This invention pertains to impact forging, and more particularly to means for performing heavy duty impact forging, this application being a continuation-in-part of application Serial No. 5 542,222, filed June 5th, 1931, which resulted in Patent No. 2,014,206, issued September 10, 1935.

An object of the invention is to provide a novel device for impact forging.

Another object of the invention is to provide a 10 machine adapted to effect a forging operation by high speed impact obtained by colliding two masses or hammers when they are traveling in opposite directions at substantially the same speed.

15 A further object of the invention is to provide a device wherein the blank is in contact with the forming dies for only a very short time.

Still another object of the invention is to provide a device wherein, after the forming has occurred, the dies will be quickly separated to permit the discharge of the formed blank.

A yet further object of the invention is to provide a device for forming heavy or other articles quickly and adequately.

25 Another object within the purview of the present invention is to provide a novel impact forging device wherein the impact transmitting members and the operating means therefor are disconnected during the movement of these members 30 toward one another to deliver a forging blow.

The present invention also comprehends the idea of providing a novel interlock between the operating means for the impact transmitting members and the means for holding such members in a position to deliver a forging blow whereby the operating means for these members is rendered inoperative to move the same before the holding means may be manually manipulated to release their engagement with the impact members.

40 Other objects, features, capabilities and advantages are comprehended by the invention, as will later appear and as are inherently possessed thereby.

45 Referring to the drawings:

Figure 1 is a view in side elevation of a device embodying the invention, a portion of the springs being broken away at the right side of the figure to show the coupling mechanism;

50 Figure 2 is a view in side elevation of the device shown in Figure 1, with the impelling mechanism omitted;

Figure 3 is a top plan view of the device shown in Figure 2;

55 Figure 4 is a transverse section elevation

through the track of the device illustrated in Figures 1 to 3 inclusive, showing the hammer disposed at the left of said figures;

Figure 5 is a top plan view of another device made in accordance with the present invention; 5

Figure 6 is a view in side elevation of the device shown in Figure 5 of the drawings;

Figure 7 is a view in end elevation of the device shown in Figure 5 of the drawings; and

Figure 8 is a view in cross-section taken in the 10 plane represented by line 8—8 of Figure 5 of the drawings.

Referring now more in detail to the drawings, a device made in accordance with the present invention is shown in Figures 1 to 4 inclusive as 15 including a track 2 which is mounted adjacent the pit 4, the track as shown being of deep channel construction and provided with inwardly extending track members 6 on which oppositely facing hammers 8 and 10 are mounted, said 20 hammers being provided with suitably disposed lugs 12 adapted to receive fastening means 14 for securing the dies 16 and 18 to the respective hammers. The hammers are provided with track engaging channel members which may take the 25 form of underframes 20 embracing the track members 6 for guiding and supporting the hammers on said tracks and preventing dissociation of the hammers from the tracks. The hammers on each side thereof are provided with brackets 30 or lugs 22 adapted to be engaged by impelling mechanism which, as shown, is in the form of a series of coil springs 24 carried by the brackets 26 disposed at each end of the track 2.

The outer end of each hammer is provided with 35 a standard 28 to which a coupler latch 30 is secured, the coupler latch being held in proper position by means of the spring members 32 engaged between lugs 34 and 36 provided on the coupler 30 and the hammer. The coupler 30 is adapted 40 to be engaged by a latch member 38 carried by a support 40, the support being guided by the guide member 42 cooperating with the bracket 26, a resilient member 44 being provided with the member 40 and the bracket for cushioning the 45 latch. The support 40 is provided with an electro-magnet 46 controlled by the switch 48, the electro-magnet upon operation of the switch operating the toggle 50 whereby operation of the electro-magnet causes the toggle to lock the latch 50 38 to the coupler 30, and a release of the electro-magnet operates to break the toggle to permit release of the latch from the coupler.

The hammer 10 is adapted to be operated by the flexible cable 52 guided on the quadrants 54 55

pivoted at 56 to the standard 58 disposed below the track 2, the cable 52 extending to and being secured to the quadrant 60 pivoted as at 62 to the standard 64 also secured below the track and substantially at the center point thereof. A similar cable 66 is secured to and passes over the quadrant 68 and to the other latch device for the hammer 8 passing over quadrants 70 similar to the above named quadrants 54. The quadrants 60 and 68 are operated through the gear segment 72 rigidly secured to the pivot at 62 and operated through the pinion 74 from a suitable power plant. The downward movement of the quadrant 72 is limited by the shock absorbing device 76.

15 The hammers as shown are provided with dies 16 and 18 for a center plate which is used by way of example. The hammer 8 is channeled at 78 to receive the piston rod 80 extending through the hammer and through an unimportant or inoperative portion of the die 16. The piston rod 80 cooperates with a blank carrier 86. The piston rod extends through the hammer 8 and is secured to the piston 81 provided in the blank carrier cylinder 82, the piston in said cylinder being controlled by compressed air or other fluid from the line 84. The blank holder member 86 is pivoted between the hammers for receiving the blank 88 and mounted in position to be contacted by the hammer 10, the holder being pivoted as 30 at 90.

35 In operation, the piston rod 80 is extended whereby the blank carrier 86 engages the blank 88 held between the hammers on the blank holder 86. The hammers are disposed at the end of their stroke by operation of the pinion 74 through the power plant to operate the quadrant 72 which draws the hammers 10 and 8, through cable 52 and the quadrants to the end of their stroke, compressing the springs 24. Release of the electro-magnet to break the toggle 48 causes release 40 of the coupler 30 from the latch device 38, permitting the springs to propel the hammers 8 and 10 toward each other. The hammer 10 will engage the blank, and continued movement will 45 cause the blank holder 86 to rotate out of the path of the hammers. The blank will not fall due to engagement of the blank by the hammer 10 and the blank carrier 86. Contact between the dies 18 and 16 will fashion the blank to its 50 proper configuration, when the rebound of the hammers will permit the dies to disengage the formed blank. The blank, of course, will have a tendency to follow the die having the largest surface, which is the die 16, but the blank will 55 be disengaged from this die by means of the blank carrier 86 aided by the recoil of the hammer 8.

60 The device disclosed in Figures 5 to 8 inclusive comprises a frame 92 adapted to support spaced channel-shaped tracks 94 and 96 upon which are mounted impact transmitting members 98 and 100. These members are supported upon the tracks 94 and 96 and are guided by the spaced rods 102 and 104 and have laterally extending 65 wing portions 106 and 108 which embrace these rods 102 and 104, respectively. The ends of the rods 102 are connected to brackets 110 and 112 mounted upon and secured to the tracks 94 and 96. The impact transmitting members are 70 moved toward one another to deliver a forging blow by means of the coil springs 114 and 116 mounted upon the rods 102 and 104, respectively, and disposed between the brackets and the laterally extending wing portions 106 and 108 of the 75 impact members.

The impact members 98 and 100 are moved to compress the coil springs 114 and 116 by means of a sliding bar 118 mounted in a suitable slot of a block secured to the inner face of the track members 94 and 96, this block providing the guide lugs 120 and 122. 5

One end of the sliding bar 118 is pivotally connected as at 124 to the end of the link 126 which has its other end pivotally connected as at 128 to a crank 130, this crank 130 being driven by a motor 132 through a gear box 134, both of which are mounted upon the frame 136 extending laterally of the frame 92 at one end thereof. Pivotally connected to the sliding bar 118 are lugs 138 and 140 adapted to engage lugs 142 and 144 disposed on the underside of the impact members 98 and 100, respectively, to move the same to compress springs 114 and 116 upon reciprocating movement of the sliding bar. 10 15

The impact members 98 and 100 are locked in 20 their "cocked" position, after the springs 114 and 116 have been compressed by the sliding bar 118, by means of the cam members 146 and 148 pivotally mounted upon shafts 150 and 152 which are provided with the notches 154 engageable 25 with lugs 156 and 158, disposed on the underside of the impact members 98 and 100. Also mounted upon the shafts 150 and 152, but rigid in respect to the cam members 146 and 148 are levers 160 and 162 which depend therefrom and are pivotally connected to the levers 164 and 166, respectively. These levers 164 and 166 are formed with hooked ends 168 and 170 adapted to be engaged by the oppositely disposed teeth 172 and 174 of the cam member 176 which is mounted 30 for rotation upon the shaft 178. Mounted upon the shaft 178, but fixed in relation to cam member 176 is a lever 180 adapted to engage the upper edge of an operating handle 182 which is pivoted for horizontal movement at 184. Operating handle 182 is normally held against movement about its pivot point 184 by means of the latch 186 which is rotatably mounted upon shaft 178. 35 40

It will be clearly apparent that inasmuch as 45 the impact members 98 and 100, when held in position as shown in Figures 5 and 6 of the drawings wherein the coil springs have been compressed, tend to exert a pressure on the cam members 146 and 148 tending to move levers 164 and 166 outwardly to cause the cam member 176 50 to rotate in a counter-clockwise direction. Inasmuch as lever 180 is fixed in relation to cam member 176 and is normally in engagement with the upper edge of the operating handle 182, these 55 impact members are held in their "cocked" position until operating handle 182 is moved in a clockwise direction about its pivot point 184, as disclosed in Figure 5 of the drawings. Operating handle 182 may be moved in this clockwise 60 direction upon release of the latch 186.

Inasmuch as the present invention comprehends the idea of entirely disconnecting the operating means for the impact members 98 and 100 65 therefrom after the same have been released from their "cocked" position, the lugs 138 and 140 have been pivotally mounted upon the sliding bar 118 and when it is desired to effect this disconnection between the lugs 138 and 140 and the impact members 98 and 100, the lugs are moved about 70 their pivot point by means of a bar 188 which, as shown in Figure 5 of the drawings, is substantially U-shaped and has its ends pivotally mounted as at 190 and 192 upon the rod 194 which is journaled in the brackets 106 and 108 75

extending inwardly from the track 94. The bar 188 has an operating handle 200 connected thereto intermediate its ends, which handle is pivoted as at 202 on the rod 194 whereby this bar 188 may be moved into engagement with the lower ends of lugs 138 and 140 to lower the same out of the path of movement of lugs 142 and 144 of the impact members 98 and 100.

The operating handle 200 is interconnected by the rod 204 with the latch member 186 to provide an interlock between the operating means for the impact members and the latch means for releasing these impact members from their "cocked" position to permit the same to travel toward one another to deliver a forging blow. This interlock is provided as a precaution to prevent any engagement between the operating means and the impact members during their travel toward one another.

It will be clearly apparent that inasmuch as rod 204 interconnects with the latch 186 and the operating handle 200, that in order to manually operate the handle 182 to effect a release of the impact members, it is necessary to move the operating handle 200 downwardly, which effects upward movement of the bar 188 into engagement with the lugs 138 and 140 to move the same out of the path of travel of lugs 142 and 144. After latch 186 has been moved to disengage operating handle 182 and the lugs 138 and 140 have been moved by the bar 188, operating handle 182 may be moved in a counter-clockwise direction about its pivot point 184, as shown in Figure 5, which movement releases lever 180 and permits counter-clockwise rotation of cam member 176. Rotation of cam member 176 permits outward movement of levers 164 and 166 which movement is transmitted through levers 160 and 162, respectively, to rotate cam members 146 and 148 whereby the lugs 156 and 158 are released from engagement with the impact members whereby the same, under the impulse of the coil springs 114 and 116, are moved to deliver a forging blow. Springs 161 and 163 interconnecting levers 160, 164 and levers 162, 166, respectively, as well as springs 165 which have one end connected to track 94 and the other end connected to levers 160 and 162, may be provided to tension these members and to assist in their return to operative position after the impact members have been released.

As shown in Figures 5, 6 and 8, each of the impact members 98 and 100 may be provided with die members 206 adjustably secured to the face thereof by means of the bolt 208, which die members, upon engagement with a metal blank and under the impulse of the coil springs, are adapted to form from this metal blank the particular forged article desired. This metal blank may be held in position between the impact members 98 and 100, as disclosed in Figures 1 to 4 inclusive, or as disclosed in application Serial No. 542,222, of which this is a continuation-in-part, and if desired the die members may be independent of the impact members and mounted upon the tracks 94 and 96, as disclosed in said application.

After the impact members have been released and the forging operation has taken place, operating handle 200 may be raised to lower the bar 188 whereby lugs 138 and 140 are rotated under the action of coil springs 210 and 212 whereby the lugs are disposed in the path of lugs 142 and 144. Upon reciprocation of sliding bar 118, the impact members are moved outwardly away from one another and the lugs 156 and 158 thereof are en-

gaged by cam members 146 and 148, respectively, which members have been previously moved into locking position by means of the cam member 176, lever 180 and operating handle 182. After the impact members have been moved into and locked in their "cocked" position, another metal blank may be disposed between the same for a forging operation, and upon release of the same as set forth above, are again moved to form the desired forged article.

While I have herein described and upon the drawings shown illustrative embodiments of the device, it is to be understood that the invention is not limited thereto but may comprehend other constructions, arrangements of parts, details and features without departing from the spirit of the invention.

I claim:

1. In a forging device, the combination of dies, a horizontally movable blank holding means for holding said blank between said dies, and means for moving said dies toward each other, one of said dies being adapted to move said first named means horizontally out of the path of movement of said die to render said means inoperative substantially at the moment of contact of one of said dies and said blank.

2. In a forging device, the combination of a track, a pair of hammers slidably mounted on said track, dies facing each other secured to said hammers, resilient members mounted adjacent said track and adapted to be engaged by said hammers, operating means, a coupler between said operating means and each of said hammers, a member pivoted out of the path of said hammers for holding a blank, holding means engaging said blank, said operating means being adapted to move said hammers to compress said coil springs, whereupon release of said couplers causes said hammers to slide toward each other and form said blank between said dies.

3. In a forging device, the combination of a track, a pair of hammers slidably mounted on said track, dies facing each other secured to said hammers, resilient members mounted adjacent said track and adapted to be engaged by said hammers, operating means, a coupler between said operating means and each of said hammers, a member pivoted out of the path of said hammers for holding a blank, holding means, said means including a cylinder, a piston mounted in said cylinder, and a piston rod engaging said blank, said operating means being adapted to move said hammers to compress said coil springs, whereupon release of said couplers causes said hammers to slide toward each other and form said blank between said dies.

4. In a forging device, the combination of a track, a pair of hammers slidably mounted on said track, dies facing each other secured to said hammers, resilient members mounted adjacent said track and adapted to be engaged by said hammers, operating means, a coupler between said operating means and each of said hammers, a member pivoted out of the path of said hammers for holding a blank, holding means, said means including a member urged toward one of said dies and engaging said blank, said operating means being adapted to move said hammers to compress said coil springs, whereupon release of said couplers causes said hammers to slide toward each other and form said blank between said dies.

5. In a forging device, the combination of a

track, a pair of hammers slidably mounted on said track, dies facing each other secured to said hammers, resilient members mounted adjacent said track and adapted to be engaged by said hammers, operating means, a coupler between said operating means and each of said hammers, a member pivoted out of the path of said hammers for holding a blank, holding means, said means including a member urged toward one of said dies and engaging said blank whereby one of said hammers engages said blank and moves it from said first named member to said other die, said operating means being adapted to move said hammers to compress said coil springs, whereupon release of said couplers causes said hammers to slide toward each other and form said blank between said dies.

6. In a forging device, the combination of a track, oppositely disposed impact transmitting members mounted on said track, die members operable under the impact received from said impact members to form to shape a metal blank disposed therebetween, and operating means for said impact members, said means including resilient means compressible by said operating means for moving said impact members upon release, said means further including means for moving said members to compress said resilient means and for holding and releasing the same, said impact members being disconnected from said last-named means during their movement to produce a forging blow.

7. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, means for holding said impact members in said position, and an interlock between said operating means and said last named means to prevent release of said impact members until after said operating means is rendered inoperative to move said impact members.

8. In a forging device, the combination of a track, oppositely disposed impact transmitting members mounted on said track, die members operable under the impact received from said impact members to form to shape a metal blank disposed therebetween, resilient means for moving said impact members upon release, reciprocating means for moving said impact members to compress said resilient means, means for holding said impact members in said position, and an interlock between said reciprocating means and said last named means to prevent release of said impact members until after said reciprocating means is rendered inoperative to move said impact members.

9. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, latch means for holding said impact members in said position, said latch means including interconnected levers, and manually operated cam means engageable with

said levers and movable to release said latch to permit movement of said impact members.

10. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, means for rendering said operative means inoperative to move said impact members, latch means for holding said impact members in said position, said latch means including interconnected levers, manually operated cam means engageable with said levers and movable to release said latch to permit movement of said impact members, and an interlock between said means for rendering said operative means inoperative and said cam means whereby said cam means can be operated only upon rendering said operative means inoperative to move said impact members.

11. In a forging device, the combination of a track, oppositely disposed impact transmitting members mounted on said track, die members operable under the impact received from said impact members to form to shape a metal blank disposed therebetween, resilient means for moving said impact members upon release, reciprocating means for moving said impact members to compress said resilient means, latch means for holding said impact members in said position, said latch means including interconnected levers, and manually operated cam means engageable with said levers and movable to release said latch to permit movement of said impact members.

12. In a forging device, the combination of a track, oppositely disposed impact transmitting members mounted on said track, die members operable under the impact received from said impact members to form to shape a metal blank disposed therebetween, resilient means for moving said impact members upon release, reciprocating means for moving said impact members to compress said resilient means, means for rendering said operative means inoperative to move said impact members, latch means for holding said impact members in said position, said latch means including interconnected levers, manually operated cam means engageable with said levers and movable to release said latch to permit movement of said impact members, and an interlock between said means for rendering said operative means inoperative and said cam means whereby said cam means can be operated only upon rendering said operative means inoperative to move said impact members.

13. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, said means comprising a power operated crank disposed outwardly of said impact members, and an operating bar reciprocated by said crank, said bar having means engaging said impact members for moving the same.

14. In a forging device, the combination of a track, oppositely disposed impact transmitting members mounted on said track, die members op-

erable under the impact received from said impact members to form to shape a metal blank disposed therebetween, resilient means for moving said impact members upon release, operating means for moving said impact members to compress said resilient means, said means comprising a power operated crank disposed outwardly of said impact members, and an operating bar reciprocated by said crank, said bar having pivotal lugs engaging said impact members for moving the same.

15. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, said means comprising a power operated crank disposed outwardly of said impact members, and an operating bar reciprocated by said crank, said bar having means engaging said impact members for moving the same, said bar having pivotal lugs engaging said impact members for moving the same, and means engageable with said lugs for moving said lugs out of the path of movement of said impact members.

30. 16. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, said means comprising a power operated crank disposed outwardly of said impact members, an operating bar reciprocated by said crank, said bar having means engaging said impact members for moving the same, said bar having pivotal lugs engaging said impact members for moving the same, means engageable with said lugs for moving said lugs out of the path of movement of said impact members, and latch means for holding said impact members whereby said resilient means is compressed, said latch means including interconnected levers, and manually operated cam means engageable with said levers and movable to release said latch to permit movement of said impact members.

45. 17. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, said means comprising a power operated crank disposed outwardly of said impact members, an operating bar reciprocated by said crank, said bar having means engaging said impact members for moving the same, said bar having pivotal lugs engaging said impact members for moving the same, means engageable with said lugs for moving said lugs

out of the path of movement of said impact members, latch mechanism for holding said impact members whereby said resilient means is compressed, said latch means including interconnected levers, manually operated cam means engageable with said levers and movable to release said latch to permit movement of said impact members, and an interlock between said last-named means and said cam means whereby said cam means can be operated only after operation of said last-named means to move said lugs out of the path of movement of said impact members.

5. 18. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, said means comprising a power operated crank disposed outwardly of said impact members, an operating bar reciprocated by said crank, said bar having means engaging said impact members for moving the same, said bar having pivotal lugs engaging said impact members for moving the same, means engageable with said lugs for moving said lugs out of the path of movement of said impact members, latch mechanism for holding said impact member whereby said resilient means is compressed, said latch mechanism including interconnected levers, a cam engageable with said levers and movable to release said levers to permit movement of said impact members, a lever connected to said cam, a lever providing a seat for said cam lever to hold said cam against movement, a latch member engageable with said last-named lever, and means between said last-named means and said latch member whereby said last-named lever is released by said latch member only after said last-named means is operated to move said lugs out of the path of movement of said impact members.

15. 19. In a forging device, the combination of a track, oppositely disposed impact transmitting members mounted on said track, die members operable under the impact received from said impact members to form to shape a metal blank disposed therebetween, resilient means for moving said impact members upon release, operating means for moving said impact members to compress said resilient means, latch mechanism for holding said impact member whereby said resilient means is compressed, said latch mechanism including interconnected levers, a cam engageable with said levers and movable to release said levers to permit movement of said impact members, a lever connected to said cam, a lever providing a seat for said cam lever to hold said cam against movement, a latch member engageable with said last-named lever, and means between said last-named means and said latch member whereby said last-named lever is released by said latch member only after said last-named means is operated to render said operating means inoperative to move said impact members.

ALFRED H. OELKERS.
